UNITED STATES PATENT OFFICE

FRED KUEHNE, JR., OF FLORA, ILLINOIS

DESIGN FOR A KITCHEN CABINET

Application filed May 1, 1933. Serial No. 47,951. Term of patent 14 years.

To all whom it may concern:

Be it known that I, FRED KUEHNE, Jr., a citizen of the United States, residing at Flora, county of Clay, Illinois, have invented a new, original, and ornamental Design for a Kitchen Cabinet, of which the following is a specification, reference being had to the accompanying drawing, forming part thereof.

The figure is a perspective view of a kitchen cabinet, showing my new design.

I claim:

The ornamental design for a kitchen cabinet as shown.

FRED KUEHNE, JR.
